SHOWER HEAD.

Richard M. Grossman, Chicago, Ill.

Application January 4, 1950, Serial No. 136,786.

19 Claims. (Cl. 299—141)

This invention relates to improvements in shower heads for bath equipments.

Objects of the invention are to provide a head which is truly simple, of extremely few parts, highly efficient and economical of water used, which is capable of producing a relatively confined divergent spray stream under all conditions of use to concentrate the same upon the part or parts sought to be sprayed, and prevent waste of water in useless side streams or excessively wide sprays that tend to strike on the walls, window sills and bathroom floors, and to confine the stream to the peripheral limits of a bathtub if used therewith or other desired areas; and in which the flowing spray streams may be conveniently adjusted and individually maintained from fine to coarse, or vice-versa, by simple manipulation of non-protruding parts which are readily accessible and out of the spray stream, thus avoiding reaching into the stream or the use of laterally projecting handles, levers or the like on the head.

Further objects of the invention are the provision, in a shower head, of means partly in the form of a threaded collar for hand-adjusting the water spray gradually by turning the collar from a generous soaking spray to a fine needle spray or to a flushing position for expelling the grit or particles that sometimes clog shower heads, or for removal of the collar entirely for a thorough cleaning of the parts; the provision of a shower head consisting of only four metal parts and one fiber or equivalent washer, which includes the mechanism for the usual ball-and-socket pipe joint as well as that for adjusting the water spray; and the provision of such a shower head in which the metal parts are adapted to be made by standard production-line methods and machines and no tools are required in their assembly or disassembly, and in which there are no inside moving parts to become rusted or incrusted in place.

Further objects are the provision of a spray head in which the shower head proper, excluding the ball joint, that is, only the parts actually causing the water to change into its spray form, consists of only two machined parts having adjustability from needle to coarse spray and being self-cleaning, and water-saving, and the provision of a single unitary core member between the ball joint and the spray head proper and having a threaded exterior for connection with the ball joint coupling at one end and for receiving the adjusting spray collar at the other end.

Further objects and advantages will appear

from the description and claims to follow, in connection with the accompanying drawings which illustrate, by way of example but not of limitation, an embodiment of the invention, and in which—

- Fig. 1 is a side view of the shower head of this invention in about the position it would normally take when connected to the usual bath equipment;
- 10 Fig. 2 is a longitudinal section of the same with the spray-adjusting collar of the shower head shown in full and dotted-line positions to cause coarse and fine spray streams to issue from the shower head;
- 15 Fig. 3 is a similar view of the shower head with the adjusting collar in a flushing stream position;
- 20 Fig. 4 is a view showing the parts individually or disassembled, in elevation and in positions to be put together or assembled, the end collars and the packing washer being in longitudinal section and the core member being partly in section;
- 25 Fig. 5 is an inner end view of the core member and showing the water passage or passages therethrough;
- 30 Fig. 6 is an end view of the shower or spray end of the device, the small ends of the spray grooves being indicated in their relation to the ends of the spray stream adjusting collar; and
- 35 Fig. 7 is a side view of the core member showing more clearly the angular relation of the spray stream grooves across the peripheral edge of the core member end section or head, so that the issuing spray streams of the water will produce a wider shower or spray stream as a whole than if the said grooves were parallel to the longitudinal axis of the core member.

Referring now in detail to these drawings, which are substantially at full scale, the usual bath installation includes a pressure water pipe 40 having a suitable control valve or valves (not shown) therein and a threaded end to which a ball coupling 41 is threadedly secured, the latter terminating in an apertured ball 42 on which the shower head is secured in such manner as to permit angular frictional adjustment of the shower head thereon while maintaining a watertight connection therewith.

The shower head of this invention includes a relatively short central unitary core member 44 having an end section or spray stream diversion member or valve plug member 45 slightly spaced therefrom, preferably by an integral portion 46.

The inner end of this solid core member 44 is recessed, as at 47, which recess may be bored,

drilled or otherwise formed therein, and is sufficiently large at its inner end substantially to encompass the aperture in the ball 12 in any angular position of adjustment of the spray head on the ball. The inner end wall of this recess is bevelled or chamfered, as at 18, to fit against the ball 12 and is preferably provided with an annular recess to receive a suitable packing material and which may take the form of a washer 19 to ensure a watertight engagement of the core member 14 with the ball 12 in any and all positions of adjustment of the core member on the ball during its change of position.

The core member 14 is thus secured to the ball 12 by a suitable socket collar 20 having an inwardly extending annular flange or lip 21 having an opening of a size to pass over the outer end of coupling 11 but too small to pass over the ball 12 thereof, as indicated in Figs. 1 and 2, and therefore engaging the same. The collar 20 is internally threaded in its outer end portion and is adapted to thread onto the inner end of the core member 14, as indicated, and thus to clamp the two together. The outer surface of collar 20 is preferably roughened or knurled, as by the longitudinal small grooves 22 shown in Fig. 1, which gives it a good finger grip for suitably tightening and loosening the same, without the use of tools, to cause the core member efficiently to be pressed against and connected with the ball to provide a watertight connection and yet permit the head to be moved and adjusted angularly on the ball, the frictional contact between the core and ball permitting such movement and maintaining the core and head in any adjusted position.

The outer surface of the coupling 11 is also preferably knurled by longitudinal grooves similar to lines or grooves 22 of the collar.

The core member is thus directly connected with the ball joint. The core member is provided with apertures 23 in any desired number, preferably four, which may be drilled or formed through the wall between the bottom of recess 17 and the space in advance of the end section 15 around the portion 16 and forming a passage for water therethrough.

The end section 15 or head of the core member 14, rigidly attached thereto and preferably integral therewith, is cylindrical, somewhat less in diameter than the exterior of the apertured portion of the member, has a relatively wide and generally smooth peripheral edge 24 forming a cylindrical surface longitudinally parallel to the axis of the member and to the exterior of the said recessed portion of said member. This peripheral edge 24 of the end section is provided with a plurality of tapered spray-stream-forming grooves or passages 25 extending longitudinally thereacross and spaced apart preferably equally, as indicated, all around the said edge. Said grooves may be triangular in cross section, as indicated, or of other form, such as round, square or the like; are preferably deepest and widest at their inner ends, that is, larger in cross section, and gradually taper and diminish in cross section to their outer ends, where, at the outer face of said section 15, they are relatively very small, preferably pin-point in size, as indicated in Fig. 6. Thus, needle-like spray streams may be produced if desired.

As will be understood, the water to form the shower spray is ejected through these grooves 25, and in order to complete the same and to confine the water thereto, the core member 14 is

provided with an adjustable sleeve or collar 26 having an internally threaded portion 27 at its inner end adapted to thread on the outer externally threaded end of the core member 14, said collar 26 having an inturned, cylindrical, flat, ring-like flange or end sleeve portion 28 of substantial width and smooth-surfaced and of a size closely to fit the said peripheral cylindrical edge 24 of the spaced end section 15 of the core member 14. The fit of the ring 28 to the said peripheral edge 24 is such as to be substantially watertight but to be rotatable thereon and slideable longitudinally thereof in the rotation of the threaded collar 26 by the hand. The collar is also preferably grooved and smoothed outwardly on the inside, as at 29, and of slightly larger diameter than the threaded portion 27 and of the stream-adjusting ring, sleeve or collar 28, for a freer movement of the water. The outer end of the adjusting collar 26 is provided with a slight forwardly projecting ring portion 31 serving as a splash guard in case a jet or jets tend to spurt transversely due to small bits of dirt in the grooves or other temporary causes.

As thus constructed, the adjustment of the ring 28 longitudinally along the peripheral edge of end section 15 of the core member determines the size and character of the spray stream issuing from the grooves 25. Thus, when the collar is out even with the outer face of the end section 15, as indicated in dotted lines 30 in Fig. 2, the streams issue in a fine, needle-like spray. When the collar is farther back, for example as shown in full lines in Fig. 2, the individual streams are larger and the spray softer. When the collar is still farther back, the spray may become a generous soaking spray. In all positions of the collar the issuing spray stream is comparatively of small diameter due to the axial parallelism of the contacting cylindrical surfaces 28 of the collar 26 and the periphery 24 of the section 15; and if the spray grooves extend across the head or section 15 parallel with the axis, of the shower head, the jets issue practically parallel thereto, though spreading outwardly somewhat as the jets try to escape from the uncovered portions of the grooves to form a slightly larger spray stream as a whole.

It is preferred, however, to provide a more divergent spray stream while still keeping it within suitable confines, such as the limits of the bathtub and away from walls, window sills, bathroom floors, and the like, and at the same time maintaining control of the individual streams or jets of the spray throughout their range of adjustment from fine to coarse and economizing in the amount of water used.

To accomplish this, the spray grooves or passages 25 extend across the peripheral edge 24 of the head or end section 15, each at a slight angle laterally to a longitudinal line therethrough parallel to the axis of the core member. Thus, in Fig. 7, the line 35 may represent the medial longitudinal line through the groove 25 and parallel to the axis of the core, and the line 36 the medial line or axis of the circumferentially offset groove 25. The angle 37 represents the lateral divergence referred to of the groove from a longitudinal line therethrough parallel to the axis of the core.

The extent of this angle 37 depends upon the divergence of the spray stream desired under the conditions prevailing. For ordinary bath shower purposes and with substantially the profile portions shown, with about 20 grooves provided

in the head and under ordinary conditions, an angle 37 of 2 to 5 degrees has been found satisfactory to produce a spray stream 8 to 12 inches in diameter at five or six feet away from the nozzle; but other angles, greater or less, may be used if desired and more or less grooves. The greater the angle the larger the cross section of the spray stream away from the nozzle.

This location of the grooves, which may be appropriately and accurately referred to as askew or helical to the axis of the core, like the rifling grooves of a gun barrel, differs, of course, from that where the grooves run straight across the edge of the head, parallel to the axis of the core, where no substantial divergence of the spray stream is secured, and also from tipped-up or expanding grooves in radial planes of the core wherein a wide, bell-like or expanded spray is obtained or control of the individual streams in the spray is lost in attempting to regulate or increase the size of the individual streams.

Such control of the individual divergent streams is due to the relative longitudinal movement of the co-operating grooved and cover members, with the grooves askew, as explained, to the axis or movement, since the cover remains in watertight contact with the surfaces at the sides of or between the grooves and confines the streams to the grooves whatever the relative longitudinal adjustment of the two members may be. For this purpose the grooves may be located in either member and the other member be smooth, either member may be relatively stationary and the other member longitudinally movable with respect thereto, and the relative longitudinal movement may be the result of the rotation of either member with respect to the other on a suitable threaded or like support or by the longitudinal sliding of either member on or with respect to the other without rotation. In all, however, the grooves extend at a lateral angle to the said longitudinal movement. Also, the nozzle parts may be other than circular in cross section if a different pattern of spray stream be desired.

Shower heads are subject to more or less clogging due to grit or particles in the water or other conditions which may cause considerable trouble and expense to clean the same and may cause replacements to be made. In the present invention, the adjusting collar may be turned to a forward position substantially as shown in Fig. 3, where the ring sleeve portion 28 of the collar 26 is forward of the end of section 15, whereby a flushing passage is formed for water all around said end section and the grooves, which suffices in most instances to flush and clean out the clogging matter. The shower head is thus self-cleaning. If, however, this does not prove sufficient, the collar 26 may be further turned and taken off entirely from the core member for a thorough cleaning of the parts. The shower head is therefore capable of being cleaned under any circumstances with very little trouble.

The adjusting collar 26 may be readily turned by the fingers without the use of tools and without getting the hand, wrist or forearm into the spray stream. The collar is preferably smooth on the exterior, as shown, though it may be knurled if desired. It is preferably made to engage the end edge of the collar 20 at its inner end, as indicated in Fig. 2 by the dotted lines 32, before the inner edge of the ring 28 reaches the outer end of the threaded portion of the core member when screwing the collar rearwardly over the end of

said member as far as it will go, and this will be before the ring 28 passes inwardly off the peripheral grooved edge of said section 15.

By this arrangement and relationship, the adjusting collar 26 is not so liable to be turned inwardly to a binding stop, tending to stick and difficult to release, since the engagement between the two collars is outside and plainly visible, whereas the edge of the ring 28 and end of the threaded portion of core 14 are inside, out of sight, and with an advantage of leverage, so that a binding stop would be more apt to be made thereby than by the two collars outside.

In operation, the water flows through the apertured ball, the recess 17 in the core member 14, through the apertures 23, and into the space before the end section 15. From there it shoots out through the grooves 25 to form the spray stream, as described.

The threaded connection of the adjusting collar with the core member 14 is of accurately well-fitted threads and is relied on to prevent leakage of water at that point. However, if desired, a watertight ring or friction washer may be added to the end edge of the adjusting collar 26 which would cling to the threads of core member 14.

As shown, the core member 14 is preferably threaded externally from end to end save for the end section 15 and preferably of the same size and type threads, and the collars 20 and 26 are internally threaded accordingly. This one common thread to connect or join all parts together in a successful operating manner makes for convenience and reduced costs.

As thus constructed, the shower head is made up of but four metal parts and a fiber washer, as shown in Fig. 4. The metal parts may be of solid brass screw-machined products or of stainless steel or other alloys. These parts, with the usual ball, constitute the mechanism for the ball-and-socket pipe joint and the mechanism for adjusting the water spray gradually from a rather generous soaking spray to a fine needle spray. By turning the spray-adjusting part still further, the shower head may be flushed. This is so simple that such flushing and self-cleaning becomes a habit and part of the usual adjusting operation. If need be, a further turn removes the collar and the parts may be scrubbed clean. No tools are required in these operations. The hands are kept out of the spray stream, and water is saved and not wasted on the walls, floors, and the like, or by failure to preserve the individual streams in the positions of adjustment for the coarser streams.

Having thus described the invention, what is claimed and desired to be secured by Letters Patent is:

1. A shower head comprising a relatively short unitary core member having a rigid outer end section, said member having a water supply connection at its inner end and a threaded exterior, an adjusting sleeve-like collar threaded on the member and having its outer end portion closely engaging the peripheral edge of said end section of the core member, a water passage in said member from the said connection to said end section, and spaced tapering spray grooves in and around one of the engaging surfaces of said adjusting collar and said end section and covered by the other surface, whereby the size of the individual spray streams issuing through said grooves may be varied by rotatively adjusting said adjusting collar.

2. A shower head comprising a relatively short

unitary cylindrical core member having a fixed spray grooved section at its outer end, said member having a socket at its inner end and a threaded exterior, said core member having a passage for water from said socket to the said section, said section having spaced spray grooves formed across the peripheral edge thereof and around the same, and a collar threaded on said member and having a portion closely fitting said edge of said section and confining emitted water from the head to said grooves to form a spray.

3. A shower head comprising a cylindrical core member having a fixed section at its outer end, said member having a socket at its inner end to receive the ball of a ball-and-socket joint in a water supply pipe and its exterior threaded to receive the socket collar of said joint to secure the core to the ball and pipe, said core having a passage for water from said socket to the said section, said section having spaced tapered spray grooves formed across the peripheral edge thereof and around the same, and an adjusting collar threaded on said member from the outer end thereof and having its outer end portion closely fitting said edge of said section with a substantially watertight engagement, said adjusting collar being adjustable lengthwise of said member by rotation thereon to cover more or less of the length of said grooves to vary the size of the water discharge openings thereof, said collar confining the emitted water from the head to said grooves whereby to form fine or coarser individual spray streams according to its said adjustment, said core member being relatively short and its threaded exterior limited in length substantially to that required for said collars.

4. A shower head comprising a single unitary cylindrical core member having a threaded exterior and spaced outer end section of slightly less diameter rigid therewith, the inner end of said member being adapted to connect with a supply pipe connection and having a water passage therethrough to said section, said end section of the core having a relatively wide peripheral edge having outwardly pointed tapering grooves across the face thereof and spaced apart around said edge, and a spray-adjusting sleeve-like collar threaded on the core from the outer end thereof and having a smooth portion closely engaging said peripheral edge of the section and covering said grooves, said collar being adjustable along the core by rotation on its threaded connection to vary the size of the individual streams issuing from said grooves to form the spray.

5. A shower head comprising a core member having a spaced fixed outer end section, said core member being externally threaded from end to end save for said section and the latter having a broad smooth peripheral edge surface slightly less in diameter than the threaded portion of the core member, the inner end of said member being adapted to engage the apertured ball of a ball-and-socket connection and a water passage therethrough to said end section, a socket collar to engage the ball and threading onto the said inner end of the core member to clamp the ball and core together in watertight and angularly adjustable relation, said peripheral edge of the end section having outwardly pointed tapering grooves across the face thereof and spaced apart around said edge, and a spray-adjusting sleeve threaded onto the core from the outer end thereof and having a smooth portion closely engaging said peripheral edge of the section and

75 its said threaded connection to cover more or less

covering said grooves, said sleeve being adjustable along the core member by turning on its threaded connection to vary the size of the streams issuing from said grooves to form the spray.

6. A shower head comprising a cylindrical core member having a spaced outer end section, said member having a water passage therethrough and being externally threaded from end to end except for said section and the latter having a broad smooth peripheral edge surface slightly less in diameter than the threaded portion of the core member, the inner end of said member being recessed and adapted to engage the apertured ball of a ball-and-socket connection, a socket collar to engage the ball and threading onto the said inner end of the core member to clamp the ball and member together in watertight and in frictional angular adjustable relation, said peripheral edge of said end section having outwardly pointed tapering grooves across the face thereof and spaced apart around said edge, and a spray-adjusting cylindrical sleeve having its inner end internally threaded to screw on the outer end of said core member, the outer end of said spray-adjusting sleeve having an internal smooth cylindrical portion engaging said peripheral edge of said end section with substantially watertight contact and rotatably and longitudinally movable thereon, the inner wall of said sleeve between the said threaded portion and the said outer smooth portion being outwardly recessed, the said sleeve being adjusted by rotation on said member to vary the size of the individual streams of water emitted through the said grooves or to position the forward edge of the said recess beyond the end of said section to enable a flushing continuous cylindrical stream of water to be emitted around the section.

7. In a shower head, a core member having a body with an outer end section having a relatively broad smooth peripheral edge surface slightly less in diameter than the body of the core, said peripheral edge having outwardly pointed tapering grooves across the face thereof and spaced apart around said edge, and a spray-adjusting sleeve-like collar threaded on the said core member and overlapping said end section, said overlapping portion of the collar having a smooth cylindrical inwardly projecting ring-like strip adapted slidingly to engage said peripheral edge with substantially watertight closeness and confining the emitted streams of water to said grooves, said collar being adjustable by rotation along the core member to adjust the size of the emitted streams through the grooves and similarly adjustable still further outwardly to uncover said grooves to provide a flushing stream passage around the said section, said collar being entirely removable from the core by further rotation to expose the core end section for thorough cleaning.

8. In a shower head, the combination of a core member having an outer end section, with a spray-adjusting collar threading onto said core member, the peripheral edge surface of said end section having tapered pointed grooves across but angled slightly off the direction of the axis of the core and spaced around the said section of the core, said collar having an internal smooth ring-like portion closely engaging the face of said peripheral edge and confining the emitted water to said grooves, said collar being adjustable longitudinally of the core by turning it on

of the length of said grooves to vary the streams therefrom from fine to coarser streams.

9. In a shower head, a single unitary cylindrical core having an external thread from end to end and a smooth spaced centrally supported end section having peripheral tapered and pointed edge grooves running slightly helicoidal of the axis of the cylindrical core, said core having a recess formed in its inner end and water passages through it into the space adjacent the said section, said core being adapted to be secured and clamped at its inner end to the apertured ball of a ball-and-socket connection by a socket collar engaging the ball and threading onto the end of said threaded core, and an adjusting collar threaded on the other end of said core and having a portion closely contacting said peripheral edge of said section to vary the size of the spray streams accordingly.

10. In a shower head, divergent spray-producing means comprising relatively longitudinally movable members in slidable watertight facial contact, and individual tapering spray stream passages in the face of one of said members and covered by the other member, said passages extending at a divergent helicoidal angle to the longitudinal direction of said movement of said members, whereby the cross-sectional size of the divergent streams issuing from the head to form the spray may be controlled by the relative longitudinal adjustment of the members and the individuality of the issuing streams be maintained by said facial contact throughout the range of adjustment.

11. A shower head comprising a cylindrical spray stream diversion member, a sleeve member surrounding the said cylindrical member in relatively slidable watertight facial contact therewith, generally longitudinal tapering spaced spray grooves in one of said members and covered by the other member, said grooves extending at an angle to the axis of said members in general helical relation thereto to produce a divergent spray in which the size of the individual streams thereof may be varied by the longitudinal adjustment of the members and the individuality of the issuing streams be maintained by such facial contact in any such position of adjustment.

12. A shower head comprising a cylindrical spray stream diversion member, a sleeve member surrounding the said cylindrical member in relatively slidable watertight facial contact therewith, generally longitudinal tapering spaced spray grooves in said cylindrical member and covered by the sleeve member, said grooves extending at an angle to the axis of said members in general helical relation thereto, whereby a divergent spray is produced by the head and the size of the individual streams thereof may be adjusted by the relative longitudinal movement of the members and the individuality of the issuing streams be maintained in any such adjustment.

13. A shower head comprising a cylindrical spray stream diversion member, a sleeve member surrounding the said cylindrical member in relatively slidable watertight facial contact therewith, a threaded connection between said members to cause said longitudinal movement by the relative rotation of said members, generally longitudinal tapering spaced spray grooves in one of said members and covered by the other member, said grooves extending at an angle to the axis of said members in general helical relation thereto, whereby a divergent spray is produced by the head and the size of the individual streams there-

of adjusted by the relative rotation of the members and the individuality of the streams maintained by the facial contact in any such adjustment.

14. A shower head comprising a core having a non-rotatable cylindrical spray stream diversion member, a sleeve member threaded on the core and surrounding the said cylindrical member in slidable watertight facial contact therewith, generally longitudinal tapering spaced spray grooves in said diversion member and covered by the sleeve, said grooves extending at an angle to the axis of said members in askew relation thereto, whereby a divergent spray is produced by the head and the size of the individual streams thereof may be adjusted by the rotation and longitudinal movement of the sleeve and the individuality of the streams be maintained in any such adjustment.

15. A shower head comprising a core member having an external cylindrical surface divided by generally parallel and generally axially-extending fluid passages circumferentially spaced about the axis of said surface, and a cylindrical sleeve

20 having an internal cylindrical surface surrounding and having relative axial movement and fluid-tight engagement with respect to the cylindrical surface of the core member and covering the said passages therein, the medial point of the exit end of each passage being circumferentially offset in general helical relation with respect to the medial point of the entrance end to the passage, the circumferential offset of the exit and entrance of the passages being in the same circumferential direction.

25 16. A shower head having a core member with an external cylindrical surface divided by generally parallel and generally axially-extending fluid passages circumferentially spaced about the axis of said surface, and a cylindrical sleeve having an internal cylindrical surface surrounding

30 and having relative axial movement and fluid-tight engagement with respect to the cylindrical surface of the core and covering the said passages therein, the axial plane through the medial point of the exit end of each passage being angularly offset with respect to the axial plane through the medial point of the entrance end to the passage, the angular offset displacement of the exit and entrance of the passages being in the same circumferential direction, said passages being generally helical.

35 17. A shower head core having an external cylindrical surface, and a cylindrical sleeve having an internal cylindrical surface surrounding and having relative axial movement and fluid-tight engagement with respect to the cylindrical surface of the core, one of said cylindrical surfaces being divided by generally parallel and generally axially-extending fluid passages circumferentially spaced about the axis of said core, said passages being generally helical.

40 18. A shower head core having an external cylindrical surface, and a cylindrical sleeve having an internal cylindrical surface surrounding and have relative axial movement and fluid-tight engagement with respect to the cylindrical surface of the core, one of said cylindrical surfaces being divided by generally parallel and generally axially-extending fluid passages circumferentially spaced about the axis of said core, the medial point of the exit end of each passage being circumferentially offset with respect to the medial point of the entrance end to the passage, the circumferential offset of the exit and en-

11

trance of the passages being in the same circumferential direction.

19. A valve head having an external cylindrical surface, a cylindrical valve sleeve having an internal cylindrical surface surrounding and having relative axial movement and fluid-tight engagement with respect to the cylindrical surface of the valve head, one of said cylindrical surfaces being divided by generally parallel and generally axially-extending fluid passages circumferentially spaced about the axis of said head, the axial plane through the medial point of the exit end of each passage being angularly offset with respect to the axial plane through the medial point of the entrance end to the passage, the angular

15

12

offset of the exit and entrance of the passages being in the same circumferential direction.
